(57) **CLAIM**

The ornamental design for a cuff gaiter, as shown and described.

DESCRIPTION

FIG. 1 is a perspective view of a cuff gaiter showing my new design in used condition;

FIG. 2 is a top view of the cuff gaiter in an open, unused condition;

FIG. 3 is a side view thereof; and,

FIG. 4 is a bottom view thereof.

The dotted lines on the cuff gaiter represent stitching. The broken lines forming the leg and boot in FIG. 1 illustrate environment and form no part of the claimed design. The broken lines on the cuff gaiter illustrate environment and form no part of the claimed design.
